ATTORNEY

UNITED STATES PATENT OFFICE.

FRED R. STAVA, OF MILROY, MINNESOTA.

SPRING-WHEEL.

1,246,177.

Specification of Letters Patent. Patented Nov. 13, 1917.

Application filed April 19, 1917. Serial No. 163,268.

To all whom it may concern:

Be it known that I, FRED R. STAVA, a citizen of the United States, residing at Milroy, in the county of Redwood and State of Minnesota, have invented certain new and useful Improvements in Spring-Wheels, of which the following is a specification.

This invention has reference to resilient wheels which employ a yielding agency other than a pneumatic tube.

A prime object is to equip the wheel with a resiliencing means which will absorb shock and jar from the wheel, which will be durable, and which can be manufactured at a 15 cost, making its commercial use practical.

Other objects as well as the nature, characteristic features and scope of my invention will be more readily understood from the following description taken in connection 20 with the accompanying drawings and pointed out in the claims forming a part of this specification.

Referring to the drawings:

Figure 1 is a fragmentary side elevational 25 view of a spring wheel constructed in accordance with my invention.

Fig. 2 is a sectional view taken on the line 2—2 of Fig. 1, looking in the direction of the arrows.

Fig. 3 is a sectional view taken on the line 3—3 of Fig. 1, looking in the direction of the arrows, and

Fig. 4 is a sectional view taken on the line 4—4 of Fig. 2, looking in the direction 35 of the arrows.

In the drawings, a hub 1 is provided which has spokes 2 radiating therefrom, these being of the usual or any desired form. Secondary spoke members are provided, and 40 are engaged with the spokes 2, the secondary spoke members comprising resilient arms 3, a pair of which are engaged with each spoke 2. The lower ends of the arms 3 embrace, and are rigidly secured to the spokes 2, 45 while the opposite ends thereof extend appreciably beyond the free terminals of the spokes 2. Portions of said arms, in proximity to the outer terminals thereof, are enlarged and have their proximate faces contoured to provide jaws 4.

A rim structure 5 is provided comprising in this instance an outer rim upon which is mounted a resilient tread portion 6. The inner periphery of the rim, has depending 55 therefrom, at intervals, ears or lugs 7. Each of the ears or lugs 7 comprises a resilient

strap which is secured to the inner periphery of the rim in any suitable manner, and has portions of the lateral margins thereof extended and reduced. Said reduced portions 60 of the lugs are turned inwardly at right angles as shown to advantage in Fig. 3 to provide a substantially U-shaped structure. Portions of the inner faces of the arms of each U-shaped member, are enlarged to provide jaws 8, as illustrated to advantage in Fig. 3.

An elastic element 9, which in this instance comprises a helical or coil spring is passed through the jaws 4 of said secondary 70 spoke structures and the jaws 8 of said lugs or ears 7. The spring has the ends thereof connected with nuts 10 which are mounted upon the opposite terminals of a bolt 11, the threads on the opposite ends of the latter 75 being of a different pitch, whereby when said bolt 11 is operated by a finger portion 12 or the like, movement will be simultaneously imparted to the nuts 10. In this way the tension of the spring can be adjusted. 80 It will be noted that the jaws 4 and 8 are corrugated to receive the convolutions of the spring, thereby preventing circumferential movement of the latter, when pressure is exerted upon the tread 6.

Bolts 13 are mounted through said secondary spoke portions 3, outside of, and also within the plane of the jaws 4, so as to permit snug engagement of the latter with the convolutions of the spring.

Clamping rings 15 are engaged with the arms of said secondary spoke members 3, so as to insure positive retention of the latter. The rings 15 are enlarged on opposite sides of the portions 3 in order to 95 prevent circumferential movement of said rings. The enlarged portions are equipped with suitable bolts, whereby the rings are normally held in snug engagement with the members 13.

The lugs or ears 7 are also equipped with suitable bolts, so that the jaws 8 thereof will also snugly embrace the springs, the latter being mounted in corresponding corrugations in said jaws.

A bracket 16 is mounted upon the rim engageable portion of each of said lugs or ear members 7, and is provided with a screw-threaded opening through which is mounted the screw-threaded shank of an 110 eye bolt 17, the latter having a nut 18 mounted thereon which abuts with the

bracket 16. Metallic cable drives 19 are used, one end of each of which is engaged with one of the eye bolts 17, while the opposite end of each is engaged with the outermost of the bolts 13 which are carried by the secondary spoke members 3.

In use it will be seen that when ordinary pressure is exerted upon the rim or thread 5 that shock will be absorbed by the elastic element 9. However, when undue pressure is applied to said tread which would be sufficient to overcome the resistance of the elastic element 9, this will be taken up by the metallic cables 19. Of course, the tension of the latter can be adjusted by movement of the nuts 18.

It will be understood that the above description and accompanying drawings comprehend only the general and preferred embodiment of my invention and that various minor changes in details of construction, proportion and arrangement of parts may be made within the scope of the appended claims without sacrificing any of the advantages of my invention.

I claim:

1. A resilient wheel including a hub equipped with radiating spokes, resilient arms embracing said spokes and extending beyond the terminals of the latter, an elas-

tic element mounted between said arms and secured thereto, and a tread engaged with said element substantially as set forth.

2. A resilient wheel including a hub, equipped with radiating spokes, resilient arms, secured to the spokes and extending outwardly beyond the terminals of the latter, the portions of said arms, beyond said spokes, being enlarged to provide jaws, an elastic element mounted between said jaws, and engaged with said arms.

3. A resilient wheel including a hub equipped with radiating spokes, arms secured to the spokes and extending outwardly beyond the terminals of the latter, the portions of said arms, beyond said spokes, being enlarged to provide jaws, an elastic element, mounted between said jaws, bolts to clamp said jaws into engagement with the elastic element, a rim in connection with said elastic element, and cables connected to said clamping bolts and extending into engagement with said rim substantially as set forth.

In testimony whereof I affix my signature in presence of two witnesses.

FRED R. STAVA.

Witnesses:

S. F. SCOTT,

H. G. CRAMER.
